UNITED STATES PATENT OFFICE.

SOAME E. PFAHLER, OF HOPEWELL, VIRGINIA.

PENCIL-HOLDER.

1,256,367.

Specification of Letters Patent. Patented Feb. 12, 1918.

Application filed October 16, 1916. Serial No. 125,918.

To all whom it may concern:

Be it known that I, SOAME E. PFAHLER, a citizen of the United States, and resident of Hopewell, in the county of Prince George, 5 Virginia, have invented certain new and useful Improvements in Pencil-Holders, of which the following is a specification.

The present invention relates to stationery and has particular reference to new and useful 10 improvements in pencil holders.

An object of my invention is to provide in a novel and cheaply constructed holder an effective and useful device for receiving, retaining and feeding a lead pencil or the like, 15 the device embodying novel and improved means for cutting a thread in a pencil whereby the same may be removed to a desired length from the holder and returned to the same after use so that the entire length of 20 the pencil may be used instead of one-half or one-third of the pencil being thrown away as is now the usual practice.

Another object of my invention is to provide a holder of the class described which 25 will firmly support a pencil in position for writing and will house and protect the pencil when not in use, as well as retain the same against loss.

A further object of my invention is to provide 30 a pencil holder having means for retaining and feeding a pencil, said means consisting of a novel arrangement of cutting elements for forming threads in the wood body of a pencil or in the composition from 35 which the pencil may be formed. My invention further contemplates the provision of a holder which may be sold with the pencil or independently thereof for use in connection with any pencil.

40 Other objects and advantages to be derived from the use of the several forms of my invention will appear from the following detailed description and the claims, taken with an inspection of the accompanying 45 drawings, in which:

Figure 1 is a perspective view of the preferred form of my invention;

Fig. 2 is an enlarged longitudinal sectional view of the feeding end thereof;

50 Fig. 3 is an enlarged fragmental perspective view of the feeding end of the same;

Fig. 4 is a longitudinal sectional view of a modified form of my invention;

55 Fig. 5 is an enlarged perspective view of a retaining clip for use in connection with the form of my invention shown in Fig. 4;

Fig. 6 is a perspective view of a further modified form of my invention;

Fig. 7 is an enlarged longitudinal section of the feeding end thereof; 60

Fig. 8 is a fragmental longitudinal section of a still further modified form of my invention;

Fig. 9 is a similar view of another modification; and 65

Fig. 10 is a similar view showing a further embodiment of the modification shown in Fig. 9.

My invention contemplates the provision of a pencil holder having a novel feeding 70 means permanently associated therewith and the preferred form of my invention is illustrated in Figs. 1 to 3, wherein the body of the holder is designated 10 and comprises preferably a cylindrical tube open at both 75 ends. The tube is provided, adjacent one end thereof, with a plurality of slots 11 arranged in spaced relation spirally, the metal struck from the body 10 to form said slots being turned inwardly to form cutting 80 edges 12.

A pencil is shown and designated 13, the same being inserted into the tube 10 from the end opposite that having the cutting element. The pencil is sharpened prior to insertion 85 and when the body of the pencil reaches the cutting members 12 the sharpened extremity thereof should project sufficiently from the end of the tube 10 to permit the same to be grasped by the user and a partial rotation 90 imparted thereto as the same is withdrawn. This action will bring the body of the pencil into contact with the cutting element 12 forming a plurality of spiral grooves in the pencil body affording the feeding means referred to. The non-cutting end of the tube 10 may be provided with a closure cap 14 so that the pencil, when not in use, may be returned to the holder and allowed to remain therein until required for further use. 100

In Fig. 4 I have illustrated a modified form of my invention, the same being designed where a composition holder is provided or where it is impracticable to form the cutting element on the holder body. In 105 this instance I provide a tubular body 15, which may be formed of hard rubber, wood or the like, the same being open at both ends. A short tubular section 16 is receivable in one end of the body 15, said section 110 being provided with an inwardly directed cutting element 17 practically identical with

the cutting element 12 hereinbefore referred to. The pencil proper is designated 18 and is inserted in the same manner in which the pencil is inserted into the body 10.

- 5 To hold the pencil when not in use I provide a short tubular retaining clamp 19 formed of a strip of metal rolled, the marginal edges thereof being in slight spaced relation as indicated at 20 in Fig. 5. To 10 lend resiliency to the body the same is provided with a slot 21 which is at a point practically diametrically opposite to the marginal edges of the blank when rolled. The member 19 as shown in Fig. 5 is to be 15 inserted into the body 15 and adhesively maintained therein. A portion of the member 19 is extended to form a tongue 22, which latter projects beyond the free end of the body 15 to provide means for engagement to release the pencil held thereby. As 20 fully illustrated in Fig. 4 of the drawings, the rolled retaining clamp 19, has one portion thereof between the slot 21 and the rolled edges, slightly inclined inwardly, to 25 form a gripping jaw. This is the normal position of the jaw, and owing to the fact that the strip is resilient the said jaw will move slightly out toward the inner surface of the holder when a pencil is positioned in 30 the retaining clamp. The retaining clamp comes into operation, when the pencil is released from the feed means at the front end of the holder 15, and the holder is then inverted, and the pencil will drop down to 35 the end in which the retaining clamp is positioned. The opposite end of the pencil will slide into the rolled strip and be wedged against the inclined jaw portion thereof. This contact will be sufficient to 40 firmly hold the pencil within the holder against rattling, but the same is adapted to be released therefrom, upon movement of the projecting tongue 22 outwardly, which will force the jaw against the inner surface 45 of the holder, hence allowing the pencil to be released upon a slight tap on said holder to drop down for engagement once more with the feed means.

Referring to Figs. 6 and 7 wherein a 50 further modified form of my invention is shown, I provide a tubular body 24, the same being open at both ends similar to the body 10. However, one free end of the margin of the body 24 is spirally cut and bent 55 inwardly to form a spiral annular blade 25, the end portions thereof being offset as at 26 owing to the spiral arrangement of the same on said body. The operation of this 60 form of my invention is practically identical with the forms of the invention hereinbefore referred to, and may be applied in the same manner as the forms shown in Fig. 4.

Referring to Fig. 8 wherein a further modified form of my invention is shown I 65 provide a tubular body 27 which may be

formed of metal or a composition as desired. The cutting element forming the feed means comprises a spirally wound strip of metal 28, the inner portion of the strip being formed to provide a cutting edge 29. The 70 strip 28 as coiled is inserted into the body 27 and may be maintained in position by soldering or other suitable fastening means. The innermost end of the strip 28 is tapered as at 30 so as to form a starting cutting edge 75 to facilitate engagement spirally with a pencil, composition or otherwise.

A still further modified form of my invention is shown in Fig. 9, the same embodying a tubular holder 32 formed of metal 80 or a composition as desired. The cutting and feeding element comprises a ring 33 receivable within the tube 32 and adapted to be secured therein adjacent one end thereof. The ring 33 is provided with a plurality of 85 spiral corrugations, the inner projecting edges thereof being sharpened to provide cutting edges 34.

A still further modified form of my invention is shown in Fig. 10, the tubular 90 body being designated 35, one free end thereof being spirally corrugated as at 36, the inner edges 37 being sharpened to provide cutters for forming threads in a pencil or the like. In this form of the invention 95 the corrugations are made integral with the body, but in the last preceding form described the corrugated ring is inserted into the body. The form of the invention shown in Fig. 9 is particularly adapted for use 100 where it is desired to employ a holder formed of wood or a composition in which the cutting elements could not be very readily formed.

I desire to direct particular attention to 105 the fact that while the detailed structures of the various forms of my invention differ, the fundamental principle of the same exists in all of the forms. It is apparent that the form of the invention shown in Fig. 1 may 110 be readily applied as shown in Fig. 4, and the gripping tongue 22 may be as readily associated with the body 10 as with the body 15. This arrangement may be embodied in the forms of the invention shown 115 in Figs. 6 to 10 without material alteration of the structure. I also desire to direct attention to the fact that the devices of my invention may be sold as independent articles, or may be sold with pencils arranged 120 therein and ready for immediate use. It is preferable that the pencil body be formed of a soft wood so as to facilitate the formation of threads therein, however, the pencil holding device may be made of sufficiently 125 strong material to allow provision of a heavy cutting element.

From the above description taken in connection with the accompanying drawings, it is thought that a clear and comprehensive 130

understanding of the construction, operation and advantages of my invention may be had, and while I have shown and described the device as embodying a specific structure, I

desire that it be understood that such changes may be made in said structure as do not depart from the spirit and scope of the invention as claimed.

Having thus fully described my invention, what I claim as new and desire to secure by Letters Patent, is:—

1. A pencil holder of the class described including a tubular body, pencil engaging means at one end thereof adapted to move a pencil into or out of the body, a rolled spring metal strip in the other end of said body, and said strip being slit longitudi-

nally, one portion forming an inwardly inclined gripping jaw adapted to engage a pencil when the same is released in said body. 20

2. A pencil holder of the class described including a tubular body, pencil engaging means at one end thereof adapted to move a pencil into and out of the body, a rolled spring metal strip on the other end of said body, said strip being slit longitudinally, one portion forming an inwardly inclined gripping jaw, and a projecting tongue on the outer end of said jaw extending from the body whereby said jaw may be released. 25 30

In testimony whereof, I affix my signature hereto.

SOAME E. PFAHLER.
